[57] CLAIM

The ornamental design for an elbow pad, as shown and described.

DESCRIPTION

FIG. 1 is a front, top and side perspective view of an elbow pad showing my new design;

FIG. 2 is a front elevational view thereof;

FIG. 3 is a rear elevational view thereof;

FIG. 4 is a side elevational view thereof; and,

FIG. 5 is a top plan view thereof.

The crosshatch shading shown in FIGS. 1-5 is understood to repeat throughout the indicated area.
